ELECTRIC SWITCH

Friedrich Menzel, Stuttgart, Germany, assignor
to Robert Bosch Aktiengesellschaft, Stuttgart,
Germany

Application October 5, 1931, Serial No. 567,079
In Germany October 9, 1930

4 Claims. (Cl. 200—102)

The present invention relates to electric switches of the combined electro-magnetic regulator and cut-out switch type suitable for electrical systems on motor vehicles, such as is disclosed in my Patent No. 1,820,361, dated August 25, 1931, for example.

In switches of this type the current coil must be kept small, corresponding to the requirements of the regulator. The automatic cut-out switch 10 consequently opens and closes in rapid succession on short-circuiting between the cut-out lead and earth, so that the switch spring and its contacts are damaged by the intermittent sparks formed thereby.

15 This disadvantage may be overcome by forming the automatic cut-out switch contact spring of bimetal strips and arranging this spring such that it will be subject to the heat of the sparks formed on opening the switch.

20 In this arrangement the bimetallic spring must, under normal conditions of working, with the switch closed, afford a definite contact pressure, so that the switch shall not open prematurely owing to vibrations of the vehicle, and it must 25 curve or bend in the desired manner on becoming heated by the sparking of the circuit-breaker.

These two properties are not always easily combined in a single spring.

The object of the present invention is to remove 30 this difficulty by securing the bimetallic spring secured to a spring of the usual material. The advantage is thereby attained that the usual spring can be selected to correspond to the desired contact pressure and the bimetallic spring corresponding to the desired sensitiveness to heat.

In the drawing an example of construction of the invention is illustrated in which:—

Figure 1 is a sectional view of the regulator switch, and

40 Figure 2 shows the contact spring of the switch on an enlarged scale.

The regulator switch is shown in Figure 1 with the switch in the open position, and apart from the construction of the contact spring is of the usual construction. The switch contact spring consists of two parts, namely, a spring *a* of the usual material and a bimetallic spring *b* riveted thereto which carries the contact *9* of the switch. The numeral *12* designates the fixed counter contact of the switch.

50 The bimetallic spring *b* curves, under the influence of the sparking of the cut-out, towards the fixed contact *12* on a short-circuit taking place, so that the switch is thereby closed. On cooling, the bimetallic spring *b* curves back again into the

position shown in the drawing in which the switch is opened.

In this construction the contact pressure on the switch can be selected for the temperatures occurring in normal working. Further, the sparks arising by the opening and closing of the switch on a short circuit are smaller than in a bimetallic spring which bends upwards on heating from the counter-contact, because the contact spring on becoming heated has the tendency to close the 10 switch.

The composition of the switch contact spring of two parts *a* and *b* enables the spring force and the curvature on heating to be obtained by this means in the desired manner.

15 Instead of riveting the bimetallic spring *b* to the spring *a*, the two may also be connected together by welding or in any suitable other manner.

The object of the invention is not limited to 20 the constructional form of the regulator switch illustrated. For example, the spring *a* instead of being fastened to the frame of the magnet may also be fastened to the armature.

I declare that what I claim is:

25 1. A combined electromagnetic cut-out and regulator for the electrical systems of motor vehicles comprising a core of magnetic material, a voltage coil and a current coil connected to the dynamo and coiled about said core, an armature, 30 means for regulating the output of said dynamo upon movement of said armature, a pair of cut-out contacts connected in series with said current coil and the battery, a bimetal spring carrying one of said contacts and a spring of a single material upon which said bimetal spring is 35 mounted.

2. A combined electromagnetic cut-out and regulator for the electrical systems of motor vehicles comprising, means for regulating the dynamo of the system, a pair of cut-out contacts, means for operating said contacts and means for preventing the operation of said contacts upon short circuiting including a bimetal spring carrying one of said contacts adapted to be heated by 45 the sparks caused by the opening of said contacts to cause the spring to distort to prevent the operation of said contacts and a single metal spring mounting for said bimetal spring whereby the desired pressure between the contacts may be 50 maintained for normal working while permitting the choice of ideal dimensions for the bimetal spring.

3. A contact member for an electromagnetic cut-out and regulator switch for the electrical 55

systems of motor vehicles comprising a bimetal spring carrying one of the cut-out contacts and a single spring supporting said bimetal spring, said bimetal spring being operated by the heat generated by sparks caused by the opening of said contacts.

4. A contact member for an electromagnetic cut-out and regulator switch for the electrical

systems of motor vehicles comprising a bimetal spring carrying one of the cut-out contacts and a single spring supporting said bimetal spring, said single spring being secured against movement at one end but being otherwise freely movable.

FRIEDRICH MENZEL.
